OTHER PUBLICATIONS

Indian First Examination Report mailed Jun. 15, 2016 for Indian design application No. 280902, a counterpart foreign application of design U.S. Appl. No. 29/537,622, 18 pages.

Primary Examiner — Cynthia Underwood

(74) Attorney, Agent, or Firm — Lee & Hayes, PLLC

(57) **CLAIM**

The ornamental design for a multi-position tablet computer case, as shown and described.

DESCRIPTION

FIG. 1 is a top view of a multi-position tablet computer case in a first position.

FIG. 2 is a bottom view of the multi-position tablet computer case in the first position.

FIG. 3 is a right side view of the multi-position tablet computer case in the first position.

FIG. 4 is a left side view of the multi-position tablet computer case in the first position.

FIG. 5 is a back view of the multi-position tablet computer case in the first position.

FIG. 6 is a front view of the multi-position tablet computer case in the first position.

FIG. 7 is a top, perspective view of the multi-position tablet computer case in the first position; and,

FIG. 8 is a bottom perspective view of the multi-position tablet computer case in the first position.

The broken lines in the drawings depict environmental subject matter and/or parts of the multi-position tablet computer case only and form no part of the claimed design.

1 Claim, 6 Drawing Sheets
